MEANS AND THE METHOD OF MAKING TYPE SHUTTLES FOR TYPEWRITING MACHINES

Henry L. Pitman, Westfield, N. J., assignor, by
mesne assignments, to Ralph C. Coxhead Cor-
poration, New York, N. Y., a corporation of
Delaware

Application March 19, 1931, Serial No. 523,920

49 Claims. (Cl. 101—401.5)

This invention relates to the production of type carriers or shuttles of the kind illustrated in my Patent No. 1,974,313, dated Sept. 18, 1934, for typewriting machines of the kind known as the Variatype.

The shuttle is formed of a piece of light weight and strong sheet metal such as duralumin or the like.

In carrying out the invention a flat blank is first stamped from a sheet of material. Said blank is then curved and suitable flanges bent in thereon at its upper and lower edges. The partially formed shuttle is then placed into a die which has types in intaglio and into which the metal is forced to form the types on the face of the shuttle.

In the present invention there is employed rolling means to engage the back of the shuttle in order to flow the metal on the opposite side 26 into the types of the die to thus form the types on the shuttle. The rolling means is reciprocatory so as to prevent flowing of the metal towards the end thereof of the shuttle.

Provision is made in the die to prevent distortion of the shuttle and to prevent the metal from flowing in the direction of rotation of the rolling means to thus prevent shearing of the types, at the end of the shuttle, from the body part of said shuttle.

Other features and advantages will hereinafter appear.

In the drawings which form part of the specification,

Fig. 1 is a plan view of the shuttle blank;

Fig. 2 is a top plan view of the partially formed shuttle;

Fig. 3 is a vertical section at the line 3—3 of Fig. 2;

Fig. 4 is a top plan view of the shuttle showing the types of the ribs formed thereon;

Fig. 5 is a vertical section taken at the line 5—5 of Fig. 4;

Fig. 6 is a rear elevation of the type shuttle;

Fig. 7 is a side elevation of the type forming machine;

Fig. 8 is a vertical section taken on the line 8—8 of Fig. 7, showing the stops to limit the movement of the rolling means;

Fig. 9 is a vertical section, taken on the line 9—9 of Fig. 7;

Fig. 10 is a front view, partly in section, of the die showing two shuttles therein;

Fig. 11 is a vertical section taken on the line 11—11 of Fig. 10;

Fig. 12 is a view similar to Fig. 10 but showing the die disassembled;

Fig. 13 is an end view of the interior of the die unit at the right in Fig. 12;

Fig. 14 is a side view of the roller carrier;

Fig. 15 is a sectional top plan view taken on the line 15—15 of Fig. 14;

Fig. 16 is a view similar to Fig. 14 but showing the two units of the roller holder separated;

Fig. 17 is an elevation of the right-hand end of Fig. 16;

Fig. 18 is an elevation of one of two detachable flanges of the die;

Fig. 19 is a similar view of the other flange;

Fig. 20 is a top plan view of a portion of the die engraving means;

Fig. 21 is a vertical section taken on the line 21—21 of Fig. 20;

Fig. 22 is a side elevation of the fixture for supporting and adjusting a die section in the engraving machine;

Fig. 23 is an end elevation of Fig. 22; and

Fig. 24 is a sectional view of a portion of one of the die sections.

Similar reference characters represent similar parts throughout the several views.

A flat blank 25, Fig. 1, of light weight material, such as duralumin, is curved to form a body part 26 and flanges 27 and 28, Figs. 2 and 3. The partly formed shuttle 29 thus produced is then placed into the circular aperture 30 of a die 31 comprising detachable sections 32, 33, 34 and 35. The die 31, after it is assembled, in a manner hereinafter described, is secured by the jaws 36 of a stationary chuck 37 which may be secured, 30 by a bracket 38, to a bed 39 of the machine.

After the die is secured to the chuck a suitable roller means 40, hereinafter described, is inserted into the aperture 30, which is reciprocated by actuating means 41 to flow the metal of the body part 26 of the shuttle into types 42 (Figs. 10 and 24) in intaglio in said die, said types being engraved in the surface bordering the aperture 30 of the die.

The roller actuating means includes a bar 43, 40 (Fig. 7) one end of which engages the roller or kneading means 40, the other end being supported by a center 44 supported in a spindle 45 of a tail stock 46 secured to the bed 39. A detachable handle 47 is supported on the bar 43 by which the latter may be rotated in opposite directions to reciprocate the roller means 40 in the die, stops 48 and 49 (Figs. 7 and 8) being provided on a fixed bracket 50, to limit the movement of the handle in both directions and thus limit the oscillations 50 of the roller means properly with respect to the shuttle being operated upon.

The die 31, as previously stated, is composed of four sections 32, 33, 34 and 35. These are rigidly held together and are provided with interlocking 55 connections between them to prevent accidental shifting thereof laterally of each other and radially of the die, and to prevent incorrect assembling of the die sections, in other words, prevent assembling of said sections except with the 60

two co-acting faces towards each other. To this end each of the sections is provided with cross tongues 51 and 52 (Figs. 10, 12 and 13) which fit into corresponding grooves 53 and 54 of the adjoining section to thus locate them with respect to each other and prevent radial and lateral shifting of said die sections. After the sections have been assembled they may be secured to a flange or ring 55 (Figs. 10 and 11) by screws 56 threaded into holes 57 in said die sections.

After the flange 55 is attached to the die two partially formed shuttles 29 are placed into the aperture 30 thereof, each being located laterally in a channel 58 (Figs. 11 and 13) formed by inwardly extending flanges 59; said shuttle blanks being located circumferentially of the aperture by gauge blocks 60 located in slots 61 and extending across the channel 58.

Another flange 62 (Figs. 11 and 19) is subsequently secured to the opposite face of the die by screws 62 which are also threaded into the holes 57. The flanges 55 and 62 are provided with grooves 63 and 64 to conform with the shape of the flanges 27 and 28 of the shuttle blank and into which said shuttle flanges fit. Thus it will be understood that the shuttle blanks are firmly secured in the die after the flanges 55 and 62 are secured thereto, to assist in preventing accidental shifting of the shuttle blanks while being acted upon by the roller means.

After the die has been assembled with the shuttle blanks therein, as above described, it may be placed in the chuck 37 which, as previously described, includes jaws 36, of which there are four, each being guided in radial slots 65 (Figs. 7 and 9), said jaws being operated simultaneously to grip or release the die 31. The die is described and claimed in my application Ser. No. 642,750 which is a division of this application.

To operate the jaws 36 of the chuck each may be provided with teeth 66 engaged by a spiral 67 formed on the face of a gear 68 which may be rotated by any one of a plurality of bevel gears 69; each gear 68 having a polygonal aperture 70 into which may be inserted a key or wrench for rotation thereby. Thus it will be understood that if the gear 68 is rotated in one direction the jaws are retracted, or, in other words, moved outwardly through the medium of the spiral 67, and if the gear 68 is rotated in the opposite direction the jaws are moved inwardly to grip the die and also center it in the chuck.

The roller means 40 includes two rollers 70 and 71 (Figs. 10, 11 and 14 to 17), the roller 70 having a shaft 72 engaging in a slot 73 of a roller carrier 74 which forms part of a roller controlling unit 75. The other roller, 71, has a similar shaft 76 engaging in a slot 77 of a carrier 78. The carrier 78 is provided with tongues 79 engaging in grooves 80 of the carrier 74 to provide a sliding connection between said carrier so that the rollers may be moved outwardly from each other at will during the rolling operation to adjust the pressure of said rollers against the shuttles, from time to time, as the rolling operation progresses.

After the roller carriers have been assembled they are contracted to their closest position so that the rollers 70 and 71 may be passed through slots 81 (Figs. 9 and 19) of the flange 62 into alignment with the channel 58 of the die. The roller unit 75 is then expanded until the rollers 70 and 71 touch the face of the shuttle blanks. Subsequently the bar 43 is inserted into a slot 82 of the roller carrier 75 (Figs. 9 and 17), said bar being rectangular in cross-section and hav-

ing slanting faces 82 (Figs. 7 and 11) engaging slanting faces 83 and 84 of the roller carriers 74 and 78, respectively. The center 44 of the tail stock is next positioned in the aperture 85 at the end of the bar 43 to assist in supporting it; the spindle 45 in which the center 44 is supported, being operated in the usual manner by a screw (not shown) which is rotated by a hand wheel 86.

After the parts are assembled as above described the lever 47 may be actuated back and forth between the stops 48 and 49 to actuate the roller means in the die through the medium of the bar 43; the roller 70 operating on one shuttle blank and the roller 71 on the other 15 blank, thus flowing the metal into the types 42 of the die to form the types 31 on the shuttles. From time to time the hand wheel 86 of the tail stock is operated to push the bar 43 further into the roller means to spread the roller carriers 74 and 78 due to the engagement of the inclined faces 82 of the bar 43 with the faces 83 and 84 of said roller carriers. The stops 48 and 49 are positioned with respect to the handle so that the rollers 70 and 71 travel slightly 25 beyond the ends of the shuttle blanks and not farther than the blocks 60. An advantage of alternate reversals of the movement of the rollers 70 and 71 is that it prevents cumulative 30 creep of the shuttle in the die which would otherwise result in shearing off of the types from the shuttle while being formed. With this arrangement the possibility of the rollers moving accidentally to the slots 81 and out of the channel 58 is prevented, and the shuttles are not subjected to a shock at each reversal of the operation of the pressure or roller device 40.

It will be noticed, by an inspection of Figs. 5 and 11, that there are three horizontal tiers or rows of types 31 with spaces therebetween and 40 that the die has three corresponding rows of types 87. Accordingly each one of the rollers 70 and 71 is provided with two annular grooves 88 thus dividing each roller into three sections 89, each section engaging the shuttle behind a 45 row of types so as to press only the metal from the body 26 of the blank which registers with the types. This also forms ribs 90 on the back of the shuttle which serve to reinforce the latter; said ribs being produced between the grooves 90 50 formed by the rollers. It will be understood that with this arrangement of grooved rollers less pressure is necessary than would otherwise be required to flow the metal from the blank into the types of the die.

Provision is made to limit the outward movement of the roller carriers 74 and 78 so as to control or determine the depth to which the rollers 70 and 71 may work into the shuttles and thus prevent their being rolled too thin. To this end the shafts 72 and 76 of the rollers 70 and 71 engage inner surfaces 92 and 93 formed on each of the flanges 55 and 61, when the rolling operation is complete, so that said roller carriers cannot be expanded beyond certain limits by 65 the wedge bar 43.

It will be understood, due to the confinement of the shuttles by the flanges 59, that the corners of the shuttle are protected against breaking during the operation of the rollers against 70 the back of the shuttle.

Inner surfaces 94 of the blocks 60, at the ends of the shuttle, are just flush with the surfaces of the slots 81 at the completion of a rolling operation. It should be understood that the blocks 75

60, in addition to locating the shuttle blanks in the die, serve also to prevent creeping of the metal in the direction of the length of the shuttle which tendency is produced by the action of 5 the rollers, which may otherwise result in shearing of the types from the end of the shuttle during the rolling operation.

To prevent collision of the outer ends 95 and 96 of the roller carriers 74 and 78 with the flanges 10 55 and 61 during the reciprocation of said carriers each of the roller shafts 72 and 76 is provided with flanges 97 and 98 which are located at the outside of the flanges 55 and 61 while the 15 rolling operation takes place. The flanges 97 also prevent shifting of the roller support 75 transversely of the die 31 by the action of the 20 bar 43 when the latter is moved, in the direction of the arrow in Fig. 11, to expand said roller supporting unit. Lengthwise shifting of the roller shafts 72 and 76 is prevented during the wedging 25 action of the bar 43 by the rollers 70 and 71 which, it will be remembered, engage in the channel 61 of the die.

After the completion of a rolling operation the 25 die 31 may be removed from the chuck upon the removal of the spreader bar 43. Said die may then be disassembled, as in Fig. 12, and the finished shuttles removed therefrom.

The shuttle, as previously stated, is composed 30 of duralumin which is a composition including copper and aluminum and which composition has the property of hardening by being worked or rolled. Consequently the types formed on the shuttle become hardened by the action of the 35 roller means.

The die sections 32, 33, 34 and 35 are engraved 40 individually and for this purpose each may be mounted on a fixture 100 comprising a bracket 101 which may be secured by clamps 102 to a work-table 103 of an engraving machine similar 45 to the one disclosed in the patent to Taylor No. 542,902, dated July 16, 1895.

Type patterns 104, of which there is one for 50 each type to be engraved in the die, are secured, one at a time, in a fixture 105 (Figs. 20 and 21) suitably secured to a pattern supporting table 105 of the engraving machine. The pattern 104 has a character 106 engraved therein which may be about ten times larger than the types 42 of the die. A tracer or stylus 107 engaging the pattern is secured to an arm 108 of a pantograph, not shown, which supports an engraving tool or 55 drill 109 (Fig. 23) operating on the concaved surface of the die to engrave the types 42.

The various patterns are secured in the same 60 position successively, in a manner hereinafter described. Accordingly the engraving tool 109 operates always in the same area. Consequently provision is made to letter space the die section to locate it in its various letter space positions in the same line or tier of types. Provision is also made to shift said die section to any one of the tiers or rows 110, 111 and 112 of types.

To locate the die in its various letter space 65 positions with respect to the engraving tool 109, the die section is carried by an indexing sector or support 115 (Figs. 22 and 23) upon which the die section is located by dowel pins 116 and 116^a mounted on said sector and extending into holes 70 117 and groove 53 respectively of the die sections; the die section being secured by screws 118 extending through holes 119 and threaded into the sector 115. The dowel pin 116^a in addition to locating the die sector on the sector 115 prevents 75 incorrect mounting of the die section thereon so

as to prevent engraving of the types upside down in the die sections. The sector 115 is provided with a series of holes 120 arranged in an arc struck about the axis of the shaft 116 and spaced angular distances corresponding to those between the types on the shuttle 28. A pin 121, supported in the bracket 101, is provided with a reduced end to enter any one of the holes 120 to locate and assist in holding the sector 115 in any one of its positions. A nut 122 is threaded onto 10 the shaft 116 by which the sector 115 may be permanently secured in its adjusted position.

Thus it will be understood that the die section is adjustable angularly to its various type positions. It will also be understood that, due to the 15 flat pattern 106, the types 42 engraved in the die section are formed with flat faces 123 (Fig. 23) so as to produce flat faces on the types 31 of the shuttle 28; flat faced types being highly desirable so as to prevent buckling of the work sheet by 20 said types while printing.

As illustrated in Fig. 23 the die section 33 is supported in the fixture 100 and the holes 120 to the left of the sector 115 are not used for said die section since only that portion of the die section 25 to the right of the slot 61 therein is to be engraved. When, however, either of the adjacent die sections 32, 34 is supported in the fixture 100, the holes 120 to the left of the sector 115 are used.

To facilitate the locating of the die section with 30 respect to the various tiers there is provided a gauge bar 125 secured to the table 103 by a clamp 126, and a gauge bar 127 secured to the table by a bolt 128. To locate the tier 110 of types, (Fig. 20) at the engraving tool 109, the bracket 101 35 is placed with its edge against the gauge bar 125 and the edge 130^a is placed against the gauge 127. The bracket 101 is then secured in this position by the clamps 102. When the middle tier 111 of types is to be located at the engraving tool a 40 gauge block 130 equal in width to the distance from the middle of one tier of types to the middle of the adjacent tier, is placed between the gauge 127 and the edge 130^a of the bracket 101. When the tier 112 of types is to be located at the engraving tool a gauge block (not shown) twice the 45 width of the block 130 is placed between the gauge bar 127 and the edge 130^a of the die supporting bracket; the bracket being held in each of its adjusted positions by the clamps 102. 50

Thus it will be understood that there is provided a fixture 100 comprising a sector 115 supported by a shaft 116 on a bracket 101 so that it may be adjusted about the axis of said shaft and relatively to the engraving tool 109, for the 55 various types in a tier; said fixture being adjustable as a whole lengthwise of the axis of the shaft 116 relatively to the engraving tool to shift any one of the type tiers to said tool.

The fixture 105 for holding the patterns or 60 masters 104 may be secured to a table 131 of the engraving machine, by a pair of C-clamps 131^a (Fig. 20). Said fixture comprises a base plate 132 having a transverse groove 133 therein into which the pattern 104 may be slid from one side. 65 A longitudinal groove 134 has a slide 135 located therein which, after the pattern is in position, is pushed by a finger-piece 136, towards the pattern plate 104, thus causing a tooth 137 of the slide 135 to enter a notch 138 to lock the plate 70 104 against accidental lateral shifting. A thumb nut 139 threaded on a stud 139^a secured to the base plate 132 is then tightened to clamp said slide 135 in place. Fingers 140 and 141 on the base plate 132 and slide 135, respectively, overlap the 75

edges of the pattern plate 104 to assist holding said plate in the groove 133. The pattern holding fixture 105 is parallel to the die supporting fixture 100 and they are angularly disposed on their respective tables for clearance purposes in the machine. The die holding fixture 100 and the pattern holding fixture 105 are claimed in my application Ser. No. 642,751 which is also a division of this application.

10 While certain preferred embodiments of the invention have been shown and described, it will be understood that changes in the form, arrangements, proportions, sizes and details thereof may be made without departing from the scope of the 15 invention as defined in the appended claims.

I claim:—

1. The method of forming a metal type shuttle which includes the forming of a flat blank, then curving the blank into a segment, and then forming types on its convexed surface by repeatedly rolling in opposite directions over the concaved surface thereof.

2. In a machine to form types on a segment, the combination of a curved die, having types de- 25 pressed therein, over which a blank segment may be placed to expose one surface, a roller to engage the exposed surface of the segment to force the metal at the opposite surface into the type impressions of the die, a holder for said roller, means 30 to repeatedly reciprocate said holder to carry said roller bodily back and forth over said segment alternately in opposite directions and from end to end thereof, means to limit the bodily movement of the roller in each direction to confine 35 its travel to the length of the segment, and means to adjust the pressure of the roller against said segment.

3. In a machine to form a type shuttle, the combination of a die, means to hold said die, 40 said die having a curved aperture into which may be inserted a partially formed curved shuttle, roller means to engage the shuttle to press it against the die, means to effect a reciprocatory rotative movement between the die and the roller means to flow the metal of the shuttle into the types of the die to form types on the face of the shuttle, means to limit the extent of such reciprocatory movement in both directions to confine the action of the rollers to said shuttle, and 45 means to adjust the pressure of the rollers against said shuttle.

4. In a machine to form a type shuttle, the combination of a die, said die being composed of a plurality of detachable units and having a circular aperture into which may be placed two oppositely disposed blank shuttles, types in intaglio in the face of said die extending outwardly from said aperture, means to hold the shuttles against accidental displacement in said die with 55 reference to said types, roller means to engage the shuttles and press them outwardly against said die, and means to actuate the roller means.

5. In a machine to form a type shuttle, the combination of a die, said die being composed of a plurality of detachable units and having a circular aperture into which may be placed two oppositely disposed blank shuttles, types in intaglio in the face of said die extending outwardly from said aperture, means to hold the shuttles against accidental displacement in said die with 65 reference to said types, roller means to engage the shuttles and press them outwardly against said die, means to reciprocate the roller means, said roller means including two rollers and two

roller carriers, and means to spread said roller carriers to increase the pressure of the rollers against said shuttles.

6. In a machine to form a type shuttle, the combination of a die, said die being composed of a plurality of detachable units and having a circular aperture into which may be placed two oppositely disposed blank shuttles, types in intaglio in the face of said die extending outwardly from said aperture, means to hold the shuttles against accidental displacement in said die with 10 reference to said types, roller means to engage the shuttles and press them outwardly against said die, means to reciprocate the roller means, said roller means including two rollers and two roller carriers, a wedge between said roller carriers, and means to actuate said wedge to spread said roller carriers to increase the pressure of said rollers against said shuttles.

7. In a machine to form a type shuttle, the combination of a die, said die being composed of a plurality of detachable units and having a circular aperture into which may be placed two oppositely disposed blank shuttles, types in intaglio in the face of said die extending outwardly from said aperture, means to hold the shuttles against accidental displacement in said die with 20 reference to said types, roller means to engage the shuttles and press them outwardly against said die, means to reciprocate the roller means, said roller means including two rollers and two roller carriers, a wedge between said roller carriers, and means to actuate said wedge to spread said roller carriers to increase the pressure of said rollers against said shuttles.

8. In a machine to form a type shuttle, the combination of a die, said die being composed of a plurality of detachable units and having a circular aperture into which may be placed two oppositely disposed blank shuttles, types in intaglio in the face of said die extending outwardly from said aperture, means to hold the shuttles against accidental displacement in said die with 30 reference to said types, roller means to engage the shuttles and press them outwardly against said die, means to reciprocate the roller means, and means to limit the extent of movement of the reciprocating means in both directions.

35 9. In a machine to form a type shuttle, the combination of a die, said die being composed of a plurality of detachable units and having a circular aperture into which may be placed two oppositely disposed blank shuttles, types in intaglio in the face of said die extending outwardly from said aperture, means to hold the shuttles against accidental displacement in said die with 40 reference to said types, roller means to engage the shuttles and press them outwardly against said die, means to adjust the roller means to increase the pressure thereof, and means to limit the adjustment of said roller means.

45 10. In a machine for forming a type shuttle, the combination of a die having an aperture therein, types formed on the inner surface of said die, a shuttle being placeable in the aperture against the types, roller means in said aperture to act upon the shuttle to flow the metal thereof into the types of said die, means to adjust the roller means toward the shuttle, and means on the die to limit the adjustment of the roller means to the desired thickness of the shuttle.

50 11. In a machine for forming a metal type shuttle, the combination of a die having an aperture into which a partially formed curved shuttle may be placed, types in intaglio on the inside of said aperture, means including a roller to operate on the concaved face of the shuttle to press the metal from the convexed face of the shuttle into the types of the die, said roller having 55 grooves to form ribs on the concaved surface of the shuttle.

60 12. In a machine for forming types on a curved type carrier, the combination of a die having a circular aperture, three rows of types in intaglio 65 70 75

5 on the surface of the die forming the border of said aperture, said aperture being adapted to receive a blank, and means including a roller to operate on the back side of the blank to force the metal into the types on the die, said roller having two grooves to produce ribs between the rows of types.

10 13. In a machine for forming types on a type carrier, the combination of a die comprising a plurality of sections, each section having a curved inner surface, all of the curved surfaces forming a circular aperture in said die, types in intaglio on the curved surfaces, means to hold a curved blank against the curved surfaces, roller means disposed in the aperture of said die, means to support said die, means to actuate said roller means over said blank to press the metal into said types, and means to increase the pressure of said roller means against said blank.

15 14. In a machine for forming types on a curved type carrier, the combination of a die having a circular aperture, types in intaglio on the interior surface of said die, detachable flanges on said die to hold the shuttle in place with its curved outer face against the types, a roller to operate on the back of the blank, means to reciprocate the roller, and means to adjust the roller radially outward towards the types, said flanges being effective to limit the outward adjustment of said roller.

20 15. In a machine for forming types of a curved type carrier, the combination of a die having a circular aperture, types in intaglio in the face of the die against which a curved blank may be placed, a roller to engage the back of the blank, a support for said roller, a chuck to hold said die, a cam element movable lengthwise of the axis of the roller to engage the support to adjust it and thus increase the pressure of the roller against the blank, and means to prevent displacement of the roller support by said element in the direction of movement of the latter.

25 16. In a machine for forming types of a curved type carrier, the combination of a die having a circular aperture, types in intaglio in the inner face of the die against which a curved blank may be placed, a roller to engage the back of the blank, a carrier for said roller, a chuck to hold said die, a cam element movable lengthwise of the axis of the roller to adjust the support to thus increase the pressure of the roller against the blank, a shoulder on said die to prevent axial displacement of the roller when the roller carrier is being adjusted, and flanges on said roller to prevent displacement of the roller carrier transversely of the die.

30 17. In a machine for forming types of a curved type carrier, the combination of a die having a circular aperture, two sets of types in intaglio in the inner face of said die against which two oppositely disposed blanks may be placed, two flanges on said die to form with the inner surface a circular channel, a roller carrier comprising two telescoping sections, a roller in each section, one of said flanges having two oppositely disposed slots therein through which the rollers may pass into said channel, means to expand said roller carrier to press the rollers against the blanks, and means to actuate the roller carrier to reciprocate the rollers over said blanks.

35 18. In a machine for forming types of a curved type carrier, the combination of a die having a circular aperture, two sets of types in intaglio in the inner face of said die against which two oppositely disposed blanks may be placed, two flanges

on said die to form with the inner surface a circular channel, a roller carrier comprising two telescoping sections, a roller in each section, one of said flanges having two oppositely disposed slots therein through which the rollers may pass into said channel, means to expand said roller carrier to press the rollers against the blanks, means to actuate the roller carrier to reciprocate the rollers over said blanks, and means to limit the reciprocatory movement of actuating means to an angular distance smaller than the angular distance between said slots and prevent the rollers from reaching said slots while being reciprocated.

40 19. In a machine for forming types of a curved type carrier, the combination of a die having a circular aperture, types in intaglio in the inner face of the die against which a curved blank may be placed, means including a roller to operate against the back of the blank to press the metal into said types, and devices in said die located at the ends of said blank to prevent the metal from flowing lengthwise of the blank.

45 20. In a machine for forming types of a curved type carrier, the combination of a die having a circular aperture, types in intaglio in the inner face of the die against which a curved blank may be placed, means including a roller to operate against the back of the blank to press the metal into said types, shoulders on said die to prevent the metal from flowing transversely of said blank while being acted upon by the rollers, and means to prevent the metal from flowing lengthwise of the blank.

50 21. In a machine for forming types of a curved type carrier, the combination of a die having a circular aperture, types on the inner face of said die against which surface a curved blank with flanges extending along its edges may be placed, means including a roller to act upon the back of the blank to press it against the types to form types on said blank, and means to embrace the flanges of the blank to prevent distortion thereof while being acted upon by the roller.

55 22. The combination of a die to assist in forming a type carrier of a typewriting machine, said die having a curved surface, types in intaglio on said surface, said die to receive a segmental blank, and pressure means to operate back and forth on the back of said blank to flow the material of said blank into the types of the die to form raised types on the blank.

60 23. The combination of a die to assist in forming type carriers of a typewriting machine, said die comprising four sections, each section having a concaved surface, the die when assembled having a circular aperture to receive two oppositely disposed blanks, each blank extending over the concaved surfaces of two adjacent die sections, types in intaglio in those portions of the concaved surfaces overlapped by the blanks, and means to flow the material of the blanks into the types of the die sections simultaneously to form raised types on said blanks.

65 24. In a machine for forming type shuttles for typewriting machines, the combination of a machine frame, a chuck mounted thereon, a die detachably supported in said chuck, said die having a circular aperture therein, types extending into said die from the aperture, said aperture to receive a curved shuttle, roller means extending into said aperture to engage the shuttle, means to cause a relative reciprocatory movement between the shuttle and the roller means to flow the metal of the shuttle into the types of the die to thus form corresponding types on the

shuttle, and means to limit the extent of the relative reciprocatory movement.

25. In a machine for forming type shuttles for typewriting machines, the combination of a machine frame, a chuck mounted thereon, a die detachably supported in said chuck, said die having a circular aperture therein, types extending into said die from the aperture, said aperture to receive a curved shuttle, roller means extending into said aperture to engage the shuttle, means to cause a relative reciprocatory movement between the shuttle and the roller means to flow the metal of the shuttle into the types of the die to thus form corresponding types on the shuttle, means to limit the extent of the relative reciprocatory movement, and means to adjust the roller means to vary the pressure thereof.

26. In a machine for forming type shuttles for typewriting machines, the combination of a machine frame, a chuck mounted thereon, a die detachably supported in said chuck, said die having a circular aperture therein, types extending into said die from the aperture, said aperture to receive a curved shuttle, roller means extending into said aperture to engage the shuttle, means to cause a relative reciprocatory movement between the shuttle and the roller means to flow the metal of the shuttle into the types of the die to thus form corresponding types on the shuttle, means to adjust the roller means to vary the pressure thereof, and means to render the adjusting means ineffective to thus determine the thickness of the shuttle.

27. In a machine for forming type shuttles for typewriting machines, the combination of a machine frame, a chuck mounted thereon, a die detachably supported in said chuck, said die having a circular aperture therein, types extending into said die from the aperture, said aperture to receive two oppositely disposed shuttles, means including two rollers one for each shuttle to operate thereon, said rollers being located in the die aperture, means to cause a relative reciprocatory movement between the shuttles and the rollers, means to limit the extent of the relative reciprocatory movement, roller supports, a wedge located between said supports, and means to adjust said wedge to vary the pressure of the rollers against their respective shuttles.

28. The method of forming a sheet metal type carrier which includes flowing some of the metal from the body of the carrier into intaglios of a die by repeated rolling actions on the opposite face of the carrier alternately in opposite directions to thus act on the carrier locally and progressively from one end to the other of said carrier.

29. The method of forming a sheet metal type carrier which includes the applying pressure locally to the inner face of the type carrier, progressively changing the point of application of pressure, and repeatedly reversing the operation lengthwise of the carrier to thus displace the metal in the type carrier locally and progressively from one end to the other thereof into intaglios of a die at the outer face of the type carrier.

30. In a machine to form types on a curved type carrier, the combination of a die conforming to the shape of the carrier and into which the carrier may be placed, the die having type intaglios therein, a pressure device to act against the inner face of the type carrier and to engage only a portion thereof at a time, and means to actuate the pressure device to cause it to move progressively over the inner face of the type holder while in contact therewith and successively in opposite

directions to press the material from the outer face into the type intaglios.

31. In a machine to form a type shuttle, the combination of a die, said die having a cavity into which may be placed a blank shuttle, types in intaglio in the face of said die, means to hold the shuttle against accidental displacement in said die with reference to said types, pressure means to engage the shuttle locally and press it against said die, and means whereby the pressure means may be moved repeatedly and successively in opposite directions over the shuttle. 5

32. In a machine to form a type shuttle, the combination of a die, said die having a cavity into which may be placed a blank shuttle, types in intaglio in the face of said die, means to hold the shuttle against accidental displacement in said die with reference to said types, roller means to engage the shuttle and press it against said die, means to reciprocate the roller means, said 20 roller means including two rollers and two roller carriers, one roller to engage the shuttle, means against which the other roller bears while the roller means is reciprocating, and means to engage said roller carriers to move one of them 25 outwardly with respect to the other to increase the pressure of the roller against said shuttle.

33. In a machine to form a type shuttle, the combination of a die, said die having a cavity into which may be placed a blank shuttle, types in intaglio in the face of said die, means to hold the shuttle against accidental displacement in said die with reference to said types, pressure means to engage the shuttle locally and press it outwardly against said die, means to reciprocate the 30 pressure means, and means to determine the extent of the reciprocating movement in both directions.

34. In a machine to form a type carrier, the combination of a die, said die having a cavity 40 into which may be placed a blank, types in intaglio in the face of said die, pressure means to engage the inside of the shuttle and press it outwardly against said die, means to adjust the pressure means to increase the pressure thereof, and 45 means to limit the adjustment of said pressure means to determine the thickness of the type carrier.

35. The combination of a die having a channel shaped cavity, types in intaglio in the cavity of 50 the die against which material may be placed, means in said aperture to operate on the material to press it into said types, and devices extending cross-wise of the channel in said die to confine the material lengthwise of the channel. 55

36. The combination of a die comprising a plurality of channel shaped sections, a holder for said die, said die having a cavity into which material may be placed, a plurality of type intaglios in said cavity, reciprocating means having a definite 60 range of movement to act on the material to force some of it into the intaglio to form the types of the type carrier, means on the holder to locate the die sections in definite positions with respect to the range of movement of the reciprocating means, and means between the die sections to position them with respect to each other so that the channels and the intaglios of both die sections align with each other. 65

37. The combination of a die having a channel shaped cavity, types in intaglio in the cavity of 70 the die against which material may be placed, means in said cavity to operate on the material to press it into said types, devices extending cross-wise of the channel in said die to confine the ma- 75

terial lengthwise of the channel, and means to engage the die sections to prevent their spreading while the material is being operated upon.

38. The combination of a device constituting a die having an aperture therein into which a shuttle blank may be placed, type intaglio in said aperture, a pressure device in said aperture to act on the blank locally, an element to adjust the pressure means to increase its pressure, means to oscillate one of said devices with respect to the other to cause a relative movement between the shuttle and the pressure device to press some of the material from the shuttle into the type intaglio, and means to limit the extent of movement of the oscillatory device in both directions.

39. The combination of a die having a circular aperture therein, types extending into said die from the aperture, said aperture to receive a shuttle, a pressure device including two elements located in the die aperture, means to effect a relative oscillatory movement between the shuttle and said pressure device, means to limit the extent of movement of the oscillatory device in both directions, and means to spread said elements to vary the pressure of said device against the shuttle.

40. The combination of a die having a circular aperture therein, types extending into said die from the aperture, said aperture to receive a shuttle, a pressure device in said aperture, said pressure device including two elements slidably supported by each other, a roller on one of said elements to engage said shuttle, means to effect a relative oscillatory movement between the shuttle and the pressure device, and means including a cam acting between said elements to spread them to increase the pressure of the roller against the shuttle.

41. The combination of a die having a circular aperture therein, types extending into said die from the aperture, said aperture to receive a shuttle, a pressure device including two elements located in the die aperture, means to effect a relative oscillatory movement between the shuttle and said pressure device, means to spread said elements to vary the pressure of said device against the shuttle, and means to limit the extent of spreading of said elements in accordance with desired thickness of the shuttle.

42. The combination of a die having a circular aperture therein, types extending into said die from the aperture, said aperture to receive a shuttle, a pressure device in said aperture, said pressure device including two elements slidably supported by each other, a roller on one of said elements to engage said shuttle, each element having a slot therein to form a rectangular aperture in the pressure element, a wedge rectangular in cross-section to fit into said aperture, means to oscillate said wedge and thereby oscillate the pressure element, and means to actuate the wedge transversely of said elements to spread them and thus increase the pressure of said device against the shuttle.

43. In a machine for forming types on a type shuttle of a typewriting machine, the combination of a die, means to hold said die, said die having a circular aperture, types extending into said die from said aperture, said aperture adapted to receive a shuttle blank, roller means to oper-

ate in said aperture against said shuttle, means to reciprocate said roller means, means to limit the extent of movement of the roller means in both directions, and means extending through the reciprocating means to increase the pressure of the roller means against the shuttle.

44. In a machine for forming types on a type shuttle of a typewriting machine, the combination of a die, means to hold said die, said die having a circular aperture, types extending into said die from said aperture, said aperture adapted to receive a shuttle blank, roller means to operate in said aperture against said shuttle, a support for the roller means, means to reciprocate said roller means through the medium of said support, and means extending through said support to increase the pressure of the roller means against the shuttle.

45. The combination of a die to assist in forming a type carrier, said die being composed of a plurality of detachable sections, interlocking connections between said sections which serve also to prevent incorrect assembling of the die sections, said die having a cavity therein to receive a blank, types in intaglio on the face of said cavity, means to secure said sections together, and means in said cavity to act on said blank to form types thereon, said interlocking connections serving also to prevent lateral and radial displacement of said sections.

46. The combination of a die to assist in forming a type carrier, said die being composed of a plurality of detachable sections, each having a curved inner surface forming part of a cylindrical opening in said die into which may be placed a blank, means between the sections to locate one with respect to the other and to insure proper end to end assembling of said sections, types in intaglio on each section, means to secure said sections together, and means to act on the blank in said die to form types thereon, the means between said sections serving also to prevent lateral and radial displacement of said sections.

47. The method of producing a metal shuttle which includes the forming of a flat blank, curving said blank into a segment, exposing the convexed face of the segment to a die having the type characters engraved thereon, and repeatedly rolling over the concaved surface and in opposite directions while the segment is exposed to said die.

48. The combination of a die to assist in forming a type carrier, said die having a cavity thereon to receive material for forming the type carrier and being composed of a plurality of detachable segments, each segment having types thereon, said segments being placeable end to end to assemble them, means to prevent incorrect assembling of said sections, means to hold said sections, and means in said cavity to act on the material to form types thereon.

49. In a machine to form simultaneously a plurality of type shuttles, the combination of a die having a circular aperture into which may be placed a plurality of segmental shuttle blanks, type in the circular face of said die, roller means to act on said shuttles and press them against the type face of said die, and means to prevent displacement of said shuttle blanks in a circular direction.
